UNITED STATES PATENT OFFICE.

GEORGE W. MULLER, OF WASHINGTON, DISTRICT OF COLUMBIA.

RAIL SUPPORT.

Application filed October 27, 1925. Serial No. 65,148.

This invention relates to railway rail supports, and has for one of its objects to increase the strength of the joint or the coupling means between the ends of the rails, to effectually resist the tendency to deflection of the rails at the point of juncture, under the severe pounding of the rolling stock.

Another object of the invention is to provide a device of this character which may be applied without structural change to rails of varying sizes and weight.

The ordinary railway rails are usually united end to end by clamping devices which lap over the confronting portions of the rails at opposite sides and bear beneath the ball or tread and against the opposite sides of the web at some distance from the ends of the rails.

The clamp devices thus constructed bear substantially the entire length against the under face of the ball and upon the upper face of the tie flange.

Experiment and observation have shown that when trains pass over the rails the pounding of the wheels of the train, especially the very heavy locomotives now in use, has a tendency to deflect the confronting ends of the rails, and if the rail ends are secured by clamp plates of the ordinary construction in contact, their whole lengths, against both the ball and the tie flanges, and rigidly connected to the webs of the rail by a plurality of relatively heavy clamp bolts, this deflection occurs, and the outer portions of the clamp plates are correspondingly humped up or elevated, and while this depression and elevation may not be evident to the eye of an observer, it is sufficient to cause a very perceptible unevenness of motion to the train.

The clamp plates as ordinarily constructed are of uniform thickness and width throughout, and when depressed or bent down opposite the rail ends, they remain in bent down position, especially if the depression is sufficient to destroy the elasticity of the metal.

When a train approaches a joint distorted as above described, the first hump or elevation in the rail causes a slight uphill movement and then down hill toward the meeting ends of the rails and then uphill again and over the second hump or elevation, and this operation being repeated by each wheel in passing aggravates the abnormal condition, and requires constant care and readjustment,

and the replacing of the impaired plates, which is a source of relatively heavy expense.

The plates in common use are relatively heavy, but the weight is not properly distributed to secure the best results, and one of the objects of the present invention is to so construct the clamp plates as to properly distribute the material by increasing the weight and thickness where the greatest strains occur and without materially increasing the weight as a whole.

Another object of the invention is to rigidly support the rails at their confronting ends and resist the tendency to deflection by the pounding or hammering of the rolling stock, and to effectually support the plates from deflection at the ends, and thus produce an arching or truss like configuration and prevent the formation of humps or elevations above the ends of the plates.

To this end the invention consists in the construction of plates which bear at a medial point beneath the balls of the rails at their meeting points, and not bearing at this medial point upon the tie flanges, and bearing at the terminals upon the tie flanges but not in contact with the balls or treads.

The clamp bolts are also so disposed as to supplement the truss like or arching construction.

In the drawings illustrative of approved forms of the construction and in which like reference characters are employed for like parts in all the views,

Figure 1 is a side elevation.

Figure 2 is a plan view with the rail portions in section on the line 2—2 of Figure 1.

Figure 3 is a transverse section on the line 3—3 of Figure 1.

Figure 4 is a transverse section on the line 4—4 of Figure 1.

Figure 5 is a transverse section on the line 5—5 of Figure 1.

Figure 6 is a transverse section on the line 6—6 of Figure 1.

Figure 7 is a detail in section on the line 7—7 of Figure 1.

Figure 8 is a side elevation illustrating a modification in the construction.

Figure 9 is a plan view of the structure shown in Figure 8.

Figure 10 is a vertical section of the clamp plates between the ends of the rails of the parts as shown in Figure 8.

Figure 11 is a vertical section through the terminal portions of the plates and through the rail as the parts are shown in Figure 8.

Figure 12 is a side elevation of the confronting ends of a pair of rails, illustrating the change necessary to adapt the form of plates shown in Figures 8, 9 and 10 to the rails.

The improved device may be applied to 10 rails of various sizes, but for the purpose of illustration is shown applied to the confronting ends of standard forms of rails including heads or treads 10, webs 11, and tie flanges 12.

15 The improved plate is formed of a body portion 13 increased in thickness intermediate the ends as shown at 14 and with a laterally directed enlargement 15 arranged to bridge over the confronting ends of the 20 rails, as shown.

It will be noted in the sectional Figure 3 that the body or middle portion of the plate comprising the enlargement 15 has its outer surface sloping downwardly and outwardly 25 from its contact with the balls of the rails. It will be observed further that the inner side of the plate as illustrated has a recess formed therein and a portion below the recess is arranged against the webs of the 30 rails. The construction described is found in practice to greatly strengthen the plate by the addition of a minimum of metal and weight thereto, and to materially aid the permanent grip of the plate upon the rails.

35 Reinforcing ribs 16 are preferably formed on the outer face of the body portion 13 and merge at the ends into the body and also into the thickened portion 14 and the enlargement 15.

40 Near their ends the body portions 13 are formed with lateral projections 17 which bear upon the upper faces of the tie flanges 12, as shown more clearly in Figure 5.

The body portion 13 is reduced in vertical 45 width toward the ends, as shown in Figures 1 and 8.

By this arrangement, it will be noted, the 50 plates bear by their thickened and reinforced medial portion against the under face of the head portions 10 of the rails, but are spaced from the tie flanges below the enlargement, as shown in Figure 3, and bear at the ends by the projections 17 upon the tie flanges 12, but do not engage the 55 balls of the rails at the terminals of the plates, as shown in Figure 5.

The upper ribs 16 are arranged reversely oblique to the longitudinal axis of the plates, and thus coact with the medial enlargement 60 to accentuate the truss-like form of the plate.

Clamp bolts 18 extend through the plates and the webs of the rails, and firmly bind the parts together, the apertures for the 65 bolts in the webs of the rails may be elong-

gated in the usual manner to provide for the expansion and contraction.

In Figures 8 to 12, a slightly modified construction is shown consisting in forming the body 13 with a single reinforcing rib 19 and with the enlargement 15 of one of the plates formed with an upwardly directed extension or lip 20 to bear against the sides of the heads 10 of the rails at each side of the confronting ends, the lip being on the plate 75 which engages the outer side of the rail only to avoid interfering with wheel flanges.

A clamp bolt 21 extends through the enlargements 14, the ends of the webs of the rails being formed with cut out portions to receive the bolt. This central bolt 21 is employed in addition to the other clamp bolts.

The clamp bolts 18 near the ends of the plates are disposed at a lower point than the other bolts, with the centre lines of the bolts in alignment with the centre lines of the adjacent bolts and the upper ends of the enlargements 14, to complete the trussing arrangement.

In the modified construction the adjacent 90 portions of the heads of the rails are cut away in any suitable manner with the cut out portions inclined inwardly and upwardly and the adjacent portions of the enlargements 15 correspondingly inclined, as shown 95 in Figures 10 and 12, so that the downward pressure imparted to the rails by the rolling stock will draw the plates inwardly, and thus materially assist in binding the parts together and preventing them from being forced away from the rails. The clamp bolt 21 supplements the binding action of the inclined portions 22 and materially increases the grip between the parts.

This is an important feature and materially increases the utility and efficiency of the 105 invention.

By the construction shown the main bearing is disposed directly beneath the rail heads at their meeting points and the plates with their enlargements meet in pyramidal outline, and bear up under the load and hold up the rail, and being enlarged laterally the greatest resistance is disposed where most needed.

What is claimed and desired to be secured by Letters Patent is:—

1. The combination with two meeting rails, of a clamp plate formed with its middle portion widest and thickest and arranged to bear against the under surfaces of the balls of the rails at the joint thereof, the said plate having widened terminal projecting portions constructed to rest upon the tie flanges of the rails, the lower edge of the said plate between the said terminal portions being spaced above the said flange, and bolts for securing the plate and rails together.

2. The combination with two meeting 130

- rails, of a clamp plate formed with its middle portion widest and thickest and arranged to bear against the under surfaces of the balls of the rails at the joint thereof, the said plate having widened terminal projecting portions constructed to rest upon the tie flanges of the rails, the lower edge of the said plate between the said terminal portions being spaced above the said flange, 5 and bolts arranged to secure the plate and rails together including a bolt passing between the ends of the rails.
3. The combination with two meeting rails, of a clamp plate formed with the middle portion increased in width and thickness and arranged to bear upon the contiguous ends of the rails, the lower edge of the said thickest portion being spaced above the tie flanges of the rails, the said 10 plate having terminal projecting portions constructed to fit upon the tie flanges of the rails, and bolts securing the ends of the plate to the rails, and bolts arranged to secure the middle of the plate to the rails 15 including a bolt passing between the ends of the rails, the said bolt being located immediately beneath the balls of the rails and acting to clamp the middle portion of the plate thereto.
- 30 4. The combination with two meeting rails, of a clamp plate formed with the middle portion thickened and arranged at the meeting point of the rails, the said thickened portion of the plate having an upwardly directed lip bearing against the sides of the balls of the meeting rails and terminating below the tops of the rails, the lower edge of the said thickest portion being spaced above the tie flanges of the rails, 35 the said plate having terminal projecting portions arranged to bear upon the tie flanges, and bolts for securing the plates and rails together.
5. The combination with two meeting rails, of a clamp plate formed with the middle portion thickened and arranged at the meeting point of the rails, the said thickened portion of the plate extending across the meeting line of the rails and below the 40 balls of the rails, the said thickened portion having an upwardly directed lip bearing against the sides of the balls of the meeting rails and terminating below the tops of the rails, the lower edge of the said thickest portion being spaced above the tie flanges of the rails, 45 the said plate having terminal projecting portions constructed and arranged to bear upon the flanges of the rails, and bolts for securing the plate and rails together.
- 55 6. The combination with two meeting rails, of a clamp plate formed with the middle portion thickened and arranged at the meeting point of the rails, the said thickened portion in contact with the balls of the rails and sloping exteriorly downwardly and outwardly from the balls of the rails to increase the strength of the plate.
7. The combination with two meeting rails, of a clamp plate formed with its middle portion in contact with the balls of the rails, the exterior of the said middle portion of the plate sloping downwardly and outwardly from the balls of the rails, and the inner side of the plate having a recess and a portion below the recess arranged against the webs of the rails.
8. The combination with two meeting rails, of a clamp plate having a middle portion in contact with the balls of the rails 120 and sloping exteriorly downwardly and outwardly from the balls of the rails, and the inner side of the plate having a recess and a portion below the recess arranged against the webs of the rails.
9. The combination with two meeting rails, of a clamp plate having its middle portion thickened and arranged at the meeting ends of the rails, the said thickened portion of the plate extending across the meeting line of the rails and below the balls of the rails, the said thickened portion having an upwardly directed lip bearing against the sides of the balls of the meeting rails and terminating below the tops of the rails, the lower edge of the said thickest portion being spaced above the tie flanges of the rails, 125 the said plate having terminal projecting portions constructed and arranged to bear upon the tie flanges of the rails, and bolts arranged in pairs for securing the said rails and plate together, a pair of bolts being located at either end of the plate and one pair of bolts being situated at the middle portion of the plate and the members of said pair of bolts passing through the end portions of different rails, and a bolt passing through the meeting line of the ends of the rails.
10. The combination with two meeting rails, of a clamp plate formed with its middle portion thickened and arranged at the meeting ends of the rails, the said thickened portion of the plate extending across the meeting line of the rails and below the balls of the rails, the said thickened portion having an upwardly directed lip bearing against the sides of the balls of the meeting rails and terminating below the tops of the rails, the lower edge of the said thickest portion being spaced above the tie flanges of the rails, 130 the said plate having terminal projecting portions constructed and arranged to bear upon the tie flanges of the rails, and bolts arranged in pairs for securing the said rails and plate together, a pair of bolts being located at either end of the plate and one pair of bolts being situated at the middle portion of the plate and the members of said pair of bolts passing through the end portions of different rails, and a bolt passing through the meeting line of the ends of the rails.

portion in contact with the balls of the rails and the end portions of the plate bearing upon the tie flanges of the rails, the exterior of the said middle portion of the plate sloping downwardly and outwardly from the balls of the rails to increase the strength of the plate.

12. The combination with two meeting rails, of a clamp plate having its middle portion in contact with the balls of the rails and the end portions of the plate bearing upon the tie flanges of the rails, the exterior of the said middle portion of the plate sloping downwardly and outwardly from the balls of the rails, and the inner side of the plate having a recess and a portion below the recess arranged against the webs of the rails.

13. Clamp plates each formed with an intermediate portion to bear beneath the balls of rails and spaced from the flanges of the same and with terminal portions to bear upon the flanges of the rails, clamp bolts operating through the terminal portions of the plates and the webs of the rails, and clamp bolts operating through the plates and the webs of the rails and spaced from

the terminal bolts and in alignment with the same and the ball engaging portions.

14. Clamp plates each formed with an intermediate portion to bear beneath the balls of rails and spaced from the flanges of the same and with terminal portions to bear upon the flanges of the rails and spaced from the balls thereof, clamp bolts operating through the terminal portions of the plates and the webs of the rails, and clamp bolts operating through the plates and the webs of the rails and spaced from the terminal bolts and in alignment with the same and the ball engaging portions.

15. The combination with railway rails having the lower faces of the balls thereof inclined inwardly and upwardly at the ends, of clamp plates having their intermediate portions inclined to correspond to the inclined portions of the rails and engaging therein, and a clamp bolt extending through the intermediate portions of the plates, said intermediate portions being spaced from the flanges of the rails while the terminals of said plates bear upon the flanges of the rails.

In testimony whereof I affix my signature.
GEORGE W. MULLER.
